United States Patent Office

Des. 183,439
Patented Aug. 26, 1958

183,439

COMBINATION CHAIR AND DESK

Herbert E. Williams, Temple, Tex.

Application May 14, 1957, Serial No. 46,171

Term of patent 14 years

(Cl. D15—8)

Figure 1 is a perspective view of a combination chair and desk embodying my new design;

Figure 2 is a top plan view thereof;

Figure 3 is a rear elevational view thereof;

Figure 4 is a side elevational view thereof; and

Figure 5 is a bottom plan view thereof.

The dominant features of the design are shown in full lines.

I claim:

The ornamental design for a combination chair and desk, substantially as shown and described.
